UNITED STATES PATENT OFFICE.

HOWARD L. INGERSOLL, OF WHITE PLAINS, NEW YORK.

CORRUGATED WALL PLATE.

Original application filed June 7, 1923, Serial No. 643,934, now Patent No. 1,627,392, dated May 3, 1927.
 Divided and this application filed April 30, 1925. Serial No. 26,962.

The invention resides in forming corrugations or embossments in a metallic plate so as to increase its strength to resist exterior loads applied upon it. By forming 5 said corrugations or embossments integral with the plate, considerable fabrication of other parts and riveting is eliminated, and furthermore, the ultimate weight of the structure is retained at a minimum.

10 Such integrally reinforced plates are especially adaptable for end walls of railway freight cars where the shifting of the lading causes severe impacts against the end wall. These integral reinforcements also resist 15 the tendency of the plate to buckle, due to the torsional and weaving movements of the car in service. Such a plate may also be used for the floor or roof of a railway car.

Such corrugations or embossments are 20 mechanical beams and can be considered and calculated as such.

When a car is loaded with sand, grain, chats or other plastic material it imposes an equally distributed load upon these 25 beams. There are two ways of designing a beam to carry an equally distributed load so that its strength at any given point will be commensurate with the bending movement at the point; in other words, so that the 30 fibre stress will be the same at any plane crossing the beam.

First: If the beam is maintained at an equal height throughout its length its width must vary so that the contour of the sides 35 form two parabolas having their vertices at the middle of the beam and their bases coincident.

Second: If the beam is maintained at an equal width throughout its length its height 40 must vary so that its contour assumes a semi-ellipse.

My invention resides in forming an integral embossment in a plate so that the height and width are proportioned in accordance with the known theories covering beams of equal strength throughout for 45 equally distributed loads.

Another object of the invention is to provide an embossment in a plate which can readily be formed therein by a pressing 50 operation and which would cause very little wear on the dies as there is very little drag of the metal over the dies.

In the drawings:

Figs. 1 and 2 show elevation and plan 55 views respectively of my embossment wherein the width is maintained substantially the same throughout its length.

Fig. 3 shows a section on line 3—3 of Fig. 2.

Fig. 4 shows a section on line 4—4 of Fig. 2.

Fig. 5 shows a section on line 5—5 of Fig. 2.

Fig. 6 shows an end view of a railway 65 car with my invention applied thereon.

Numerical 10 designates a flat plate having an embossment 12 pressed integrally therewith which has a constant width substantially throughout its length and may be provided 70 with terminal portions 13 which vary in width and merge into the plane of the plate.

Figs. 3, 4 and 5 are cross sections showing the constant width of this beam and also show the varying height, this height varying 75 in accordance with known principles.

This is a division of my co-pending application Serial No. 643,934, filed June 7, 1923.

I claim:

1. A metallic plate having a corrugation 80 formed therein of constant width and with its height varying so that its contour forms a semi-ellipse, so that said corrugation is of uniform strength throughout its length for an equally distributed load.

2. A metallic plate having a corrugation 85 formed therein of constant width and with its height varying so that its contour forms a semi-ellipse, so that said corrugation is of uniform strength throughout its length 90 for an equally distributed load, said corrugation having terminal portions merging into the plane of the plate.

HOWARD L. INGERSOLL.
